ROTARY ELECTRICAL SWITCH

Edward H. Reinschmidt, Jr., Cedar Rapids, Iowa,
assignor to Collins Radio Company, Cedar
Rapids, Iowa, a corporation of Iowa

Application March 12, 1948, Serial No. 14,557

6 Claims. (Cl. 200—158)

1

This invention relates to electrical switches and more particularly to switches having a multiplicity of stationary contacts.

A principal object of the invention is to provide a rotary switch having a series of fixed or bank contacts arranged in a plural-turn helical path, and a cooperating rotary brush or wiper which is arranged to follow a corresponding helical path.

Another object is to provide a multi-point selector switch wherein the stationary or bank contacts are mounted and extend interiorly of a dust-proof casing; and a rotary brush or wiper is carried by a shaft extending axially through the casing. As a result of this construction, it is possible to provide the switch with any desired number of contacts arranged in a plural-turn helix while protecting both the fixed and rotary contacts from contamination by dust, moisture and the like.

A feature of the invention relates to a switch construction in the form of a cylindrical enclosing housing having a multiplicity of stationary contacts extending through the housing wall and arranged in a plural-turn helical path. A rotary wiper brush is mounted on a shaft extending centrally through the housing and this brush is carried by a member which is subjected to a combined rotary and rectilinear motion as the shaft is turned so as to cause the wiper brush successively to engage each of the stationary contacts in the several successive helical turns as the said shaft is continuously rotated.

Another feature of the invention relates to the novel organization, arrangement and relative location of parts which cooperate to provide an improved multi-turn selector switch of the dust-proof type.

Other features and advantages not particularly enumerated will be apparent after a consideration of the following detailed descriptions and the appended claims.

In the drawing which shows one preferred embodiment,

Fig. 1 is a plan view of a switch according to the invention.

Fig. 2 is a sectional view of Fig. 1, taken along the line 2—2 thereof.

Fig. 3 is a sectional view of Fig. 2, taken along the line 3—3 thereof.

Fig. 4 is a sectional view of Fig. 2, taken along the line 4—4 thereof.

Fig. 5 is a detail view of the rotor unit of the switch.

2

Fig. 6 is a longitudinal sectional view of a modification of the invention.

Fig. 7 is a sectional view of Fig. 6 taken along the line 7—7 thereof.

Fig. 8 is a detail view of the rotor of Figs. 6 and 7.

The switch comprises a cylindrical enclosing casing 1 of suitable insulating material such as a molded phenolic material having its right-hand end formed with an integral lug or knob 2 which is adapted to fit within a corresponding opening in a suitable fixed support or panel 3 to which the switch is to be fastened, in order to prevent the casing from turning as the switch rotor is turned. The casing 1 has one end closed by an integral wall 4, having a central opening into which is molded a metal bushing 5 which has its external periphery 6 threaded to receive a suitable fastening nut 7 for mounting the switch on the panel 3. The opposite end of casing 1 has seated therein a closure member 8 which may be of the same material as the casing 1, and may be fastened thereto in any convenient manner, for example by cement or by set screws. The member 8 has a central opening in which is molded a metal bearing sleeve 9 to receive the reduced circular end of the rotary shaft 10. Fastened to the inner face of member 8 by suitable eyelets or rivets 11, is a metal disc 12, which is provided with an integral lug 13 extending through the member 8. For the purpose of restraining the shaft 10 against lengthwise movement with respect to the casing, it is provided with a circular groove 14, into which is fitted a retainer ring 16. The left-hand end of shaft 10 has a flat which registers with a corresponding opening in an insulating disc or wafer 18. Attached to the disc 18 by suitable eyelets or rivets 19 is a metal disc 20, having three offset spring lugs 21 which wipe against the above-described metal disc 12 as the shaft 10 is rotated.

The portion 22 of the shaft 10 is circular in periphery so as to provide a smooth bearing surface within the bushing 5. However, the remainder of the length of shaft 10 has flats 23, 24, and registering with these flats adjacent the wall member 4 and staked to shaft 10, there is a metal member 25 carrying diametrically opposite spring arms 29, the member 25 having respective openings in which are seated the detent balls 26, 27. The balls 26, 27, cooperate with corresponding embossed notches 28, integrally molded on the inner face of member 4. Also fitted on to the shaft 10 is a rotor member 30 of suitable

insulating material having a hub portion 31 with internal flats which register with the corresponding flats on the shaft 10 so that the rotor 30 turns in unison with the said shaft but is capable of sliding longitudinally of the shaft as the shaft is being turned. A coiled copper or soft brass spring 32 has one end soldered to member 20, and the other end is soldered to a metal eyelet 43 which holds wiper 41 in place on rotor 30. The left-hand face of rotor 30 has a well 31 to receive the coil 32 when it is collapsed as the rotor 30 is moved to the left.

The longitudinal sliding or feeding movement of the rotor 30 is effected by engagement with the successive stationary contacts 34, which are mounted in the casing 1. Preferably, the internal periphery of casing 1 is provided with a continuous helical groove 35 and this groove is provided with a series of equally-spaced rectangular openings into which are fitted the several contact members 34. As shown more clearly in Fig. 3, each of these stationary contacts is in the form of a suitable spring metal such as beryllium copper having a central main contact portion 36, which extends through the corresponding rectangular opening in the casing 1. Each contact member is also provided with a pair of integral lateral lugs 37, 38, terminating in respective hooked chamfered portions 39, 40, which resiliently lock with the edges of the corresponding openings in casing 1. Thus, each of the stationary contacts is firmly anchored in the casing 1 and it has its inner contacting end extending interiorly of the casing a sufficient distance to be engaged by the rotary brush or wiper 41 which is carried by the rotor 30. The openings in the casing 1 through which the contact members 36 pass, provide a tight fit with respect thereto, so as to protect the interior of the casing from the ingress of dust, moisture and the like.

The longitudinal feeding movement of the rotor 30 is effected by means of a continuous helical slot 42 which is formed in the outer periphery of the rotor 30, the pitch of this helical slot being the same as the pitch of the helical groove 35, and therefore the same as the pitch of the path along which the various stationary contacts 34 are located. Preferably, the wiper brush 41 is attached to the rotor 30 by a suitable eyelet or rivet 43, so that the said brush is recessed below the outer peripheral surface of the rotor. However, the rotor 30 has an outer diameter which is only slightly less than the inner diameter of the casing 1, so that the helical groove 42 is at all times in registry with a series of stationary contacts 34. Consequently, as the shaft 10 is turned, it causes the wiper 41 to engage the stationary contacts 34 successively, and by reason of the helical grooved engagement between the periphery of the rotor and the corresponding helically mounted stationary contacts 34, the said contacts 34 act in the nature of a lead screw, causing the rotor 30 to be advanced along the length of shaft 10 as the latter is being turned. The axial feeding movement of the rotor is limited by the end rings 17 and 44 fitted into the corresponding grooves on shaft 10. In order to complete the electrical circuit between wiper 41 and lug 13, the spring 32 can be connected at its right-hand end to the eyelet 43 in any suitable manner, for example by soldering.

Referring to Figs. 6 and 7, there is shown a modification of the switch of Figs. 1 to 5. In general, this modified structure is the same as that of Figs. 1 to 5, except that the common

return contact members 12 and 20 at the end of the switch are deleted and are replaced by a single continuous plural-turn helical metal rib 45 which is fitted within a corresponding plural-turn helical recess on the inner periphery of the casing 1. Preferably, the rib 45 extends inwardly into the casing to the same distance as the inwardly projecting ends of the stationary contacts 34. The identical structural elements of the embodiments of Figs. 1 to 5 and Figs. 6 and 7 are designated alike. In the embodiment of Figs. 6 and 7, the rotor 30 instead of having a single helical groove 42, has a pair of parallel helical grooves 42, 46 (Fig. 8). The groove 42 receives and cooperates with the inwardly projecting ends of the stationary contacts 34 as hereinabove described, while the groove 46 receives and cooperates with the inwardly projecting end of the rib 45. The rotor 30 carries in addition to the foregoing-described wiper 41, an additional wiper 47, both of which are electrically interconnected by the common fastening eyelet 43. The wiper 47 therefore continuously engages the common return rib 45, while the wiper 41 engages the stationary contacts successively, as the shaft 10 is rotated.

While the drawing shows a rotor carrying a single wiper 41 cooperating with the stationary contacts 34, it will be understood, of course, that this rotor may carry more than one such wiper. Likewise, while the wiper 41 has a peripheral width which is less than the peripheral spacing between successive stationary contacts 34, it will be understood that if this wiper is to be of the "shorting" type, it may be made of a sufficient peripheral width so that it can engage two or more stationary contacts for each position of the shaft 10. Preferably however, the shorting action is achieved by using contacts 34 having wider contact surfaces so that adjacent contacts can be bridged by the wiper. It will be understood, of course, that the number of stationary contacts may be increased by either decreasing their circumferential spacing or by increasing the number of helical grooves and in which the additional stationary contacts are mounted, and by likewise employing a corresponding change in the size of the detent balls 26 and their associated centering bosses 28. Furthermore, if desired, the left-hand end of shaft 10 can protrude through the casing so that it may be appropriately coupled to the rotary shaft of a similar switch unit, thus permitting two or more of such units to be operated in tandem from a single knob or dial attached to shaft 10. Instead of stacking separate complete units together in end-on relation to increase the number of circuit controls, the casing 1 may be made in separate cylindrical sections which can be keyed or fastened together to form a single complete casing, depending upon the number of stationary contacts that are to be employed, and likewise the shaft 10 can be made in separate attachable sections to be keyed together to provide the extended guiding means for the rotor 30.

While certain particular embodiments have been described herein, it will be understood that various changes and modifications may be made therein without departing from the spirit and scope of the invention.

What is claimed is:

1. An electric switch comprising a cylindrical casing, a plurality of circumferentially-spaced stationary contacts carried by said casing arranged in a helical path therearound and extend-

ing inwardly thereof, a rotor drum of insulation concentrically mounted with relation to said stationary contacts interiorly of said casing, said rotor drum having a diameter approximating the internal diameter of said casing and carrying at least one wiper brush for engaging said stationary contacts as the rotor is rotated, and a single turn helical groove on the external periphery of said rotor and engaging with said contacts for subjecting said rotor to an axial feeding movement as said rotor is being rotated.

2. An electric switch, comprising a cylindrical casing, a plurality of circumferentially-spaced stationary contacts mounted in said casing along a plural turn helical path, a rotatable shaft concentrically mounted within said casing, a rotor member slidably mounted on said shaft but rotatable as a unit therewith and having a single but continuous peripheral helical groove, at least one wiper brush carried by said rotor member and successively engaging said stationary contacts as the rotor is rotated, said stationary contacts and said rotor groove engaging each other to impart a lead screw feed motion to the rotor as it is being rotated.

3. An electric switch, comprising a cylindrical casing, a continuous rib on the inner periphery of said casing in the form of a plural turn helix, a plurality of stationary contacts mounted in said casing and located in the path of a plural turn helix with the inner ends of the contacts extending radially inward of the casing, a rotatable shaft passing centrally through said casing, a rotor carried by said shaft for sliding movement thereon and for rotation as a unit therewith, said rotor carrying a pair of wiper brushes one of which engages said helical rib and the other of which engages said stationary contacts as the said shaft is rotated said rotor having means to advance said wipers axially of said shaft as it is being rotated.

4. An electric switch according to claim 3, in which said rotor has a pair of parallel helical grooves on its periphery having the same pitch as said helical rib, one of said grooves receiving and cooperating with the stationary contacts and the other groove receiving and cooperating with said stationary rib to effect said axial movement of the rotor as said shaft is rotated.

5. An electric switch comprising, a cylindrical casing, a plurality of stationary contacts anchored in said casing along a plural turn helical path

- each contact having a portion extending radially inward of the casing, a shaft rotatably mounted in the end walls of the casing, a rotor member slidably mounted on said shaft but rotatable as a unit therewith, at least one wiper brush carried by said rotor, means normally biasing said rotor towards one end of the casing, and means responsive to the rotation of said shaft to cause said rotor to undergo a combined rotary motion and axial feed motion whereby said wiper successively engages said stationary contacts, one end wall of the casing carrying a fixed contact plate which engages a rotary contact member mounted on said shaft, and the said means for normally biasing the rotor towards one end of the casing comprises a spring which at one end is in electrical engagement with said rotary contact member and at the opposite end with said wiper.
- 10 6. An electric switch comprising, a cylindrical casing, a plurality of stationary contacts anchored in said casing along a plural turn helical path each contact having a portion extending radially inward of the casing, a shaft rotatably mounted in the end walls of the casing, a rotor member slidably mounted on said shaft but rotatable as a unit therewith, at least one wiper brush carried by said rotor, means normally biasing said rotor towards one end of the casing, and means responsive to the rotation of said shaft to cause said rotor to undergo a combined rotary motion and axial feed motion whereby said wiper successively engages said stationary contacts, said rotor having a peripheral helical groove of the same pitch as said helical path, and said wiper is mounted in said rotor and in communication with said groove so as to be below the external periphery of said rotor but engageable with said stationary contacts as the rotor is turned.
